ATTORNEY

UNITED STATES PATENT OFFICE.

HOWARD MASON, OF SAXONVILLE, MASSACHUSETTS.

PILE-FABRIC LOOM.

Application filed December 16, 1926. Serial No. 155,286.

This invention relates to looms for weaving pile fabrics, such as Wilton or the like, wherein a multiplicity of figuring pile warp threads are selectively formed into loops over pile wires to form a figuring or pattern effect upon the surface of the cloth.

In weaving this general character of pile fabric as now ordinarily practiced, the figuring pile warp shed is closed or substantially closed prior to the full beat-up movement of the lay, in order to carry the selected figuring pile warp threads about the pile wire previously in the shed and maintain the pile wire in its pile forming position. Inasmuch, however, as those figuring pile warp threads not raised in accordance with the pattern desired float in the body of the fabric and consequently become slack, such slackness is manifested in the pile loops when the order of the figuring pile warp shed is changed, with the result that when the pile loops are cut, an uneven pile surface is liable to be produced. In attempts to overcome this condition, it has heretofore been the practice to impart to the lay two beat-up movements, either of the same or different extent, with consequent loss of fabric production.

One of the objects of the present invention, therefore, is to overcome the difficulties heretofore experienced in the weaving of Wilton and like pile fabrics, eliminate the slackness heretofore present in the figuring pile warp threads during the formation of the pile loops and to increase the output of the loom by driving up both the pile wire and weft thread by a single beat-up movement of the lay. In accordance with the present invention, those figuring pile warp threads, which are raised in accordance with the pattern to form pile loops are placed under tension to take up the slack, and such tension is maintained during the beat-up movement of the lay to carry the pile wire to the fell of the cloth, the result being that a single beat-up movement of the lay affects the pile forming loops uniformly throughout the fabric.

More specifically stated, the present invention contemplates the employment of a jacquard mechanism having a griff for selectively raising certain of the figuring pile warp threads, and means for operating the

griff or raising it and maintaining it raised with the lifted figuring pile warp threads under tension until the lay has completed or substantially completed its beat-up movement to carry the pile wire to the fell of the cloth and in connection with such jacquard mechanism, the ground warp threads are controlled by harness mechanism for producing the ground shed for the insertion of the weft.

In carrying out the essentials of the present invention, the griff is actuated from a cam having a dwell portion which serves to maintain the griff in elevated position until the pile wire has been inserted in the figuring pile warp shed and the lay has completed or substantially completed its beat-up movement, whereupon the cam operates to close the figuring pile warp shed as the lay goes back. In connection with such dwell cam portion of the griff, the present invention further contemplates cam means having a dwell of somewhat less extent for controlling the comber board to position other figuring pile warp threads to float within the body of the fabric.

The invention and new combination of parts will best be made clear from the following description and the accompanying drawings of one good form thereof, it being understood, of course, that variations may be made in details without departing from the essentials of the present invention.

In the drawings:

Fig. 1 is a perspective side view of a pile fabric loom containing the present invention;

Fig. 2 is an enlarged detail showing the relation of the figuring pile warp threads and ground warp threads upon the insertion of the pile wire and weft thread;

Fig. 3 shows the relation of parts during the beat-up movement of the lay, the loop forming figuring warp threads being raised and under tension; and

Fig. 4 is a detached detail at the head of the jacquard.

The loom frame 1 may be of usual construction having the arch 2 for the harness mechanism 3 which operates the heddles or harnesses 4 for control of the ground warp threads. The harness mechanism and its op-

erating means may be of usual construction, the essentials in this regard being that the ground shedding mechanism operates to produce the ground shed for the insertion of 5 the weft threads.

Mounted in suitable bearing 5 at the lower part of the loom frame, as shown, is the driving shaft 6 which may be actuated from any usual source of power, and mounted 10 upon the driving shaft 6 is the bevelled gear 7 which meshes with a bevelled pinion 8 on the shaft 9. Fixed to the shaft 9 is the gear 10 which meshes with a smaller gear 11 secured to the crank shaft 12, which 15 extends transversely of the loom, and connected with the crank shaft 12 are the pitmen 13, one at each side of the loom, which actuate the lay 14 to effect its beat-up movements. Since the fabric produced by the 20 loom shown is wide and may be in the form of a rug or the like, the torque on the crank shaft may be relieved and the crank shaft operate both ends of the lay more effectively by driving the crank shaft at each end there- 25 of, although it may not always be necessary. In the present instance of the invention, however, the crank shaft has secured thereto the gears 15, one at each side of the loom, which mesh with the smaller gears 16 on 30 the transverse shaft 17, the result being that the crank shaft receives similar impulses at each side of the loom, a condition desirable when weaving rugs or wide fabrics.

The pile wire inserting mechanism is 35 shown only in part and comprises the flexible connection 18 and pulley 19. Further details of the pile wire inserting mechanism appear unnecessary because the details thereof form no part of the present invention 40 and may be of usual character for inserting pile wires in the figuring pile warp shed.

The jacquard mechanism except in so far as herein further explained may be of usual construction and comprises the overhead frame 20 and cross-girders 21 for supporting the parts of the jacquard mechanism. The jacquard includes a griff 22 which may 45 also be of usual construction, but in accordance with the present invention the griff is given movement such that when the jacquard selects the desired figuring pile warp threads to form the pattern in pile loops, the griff is raised and maintained raised to produce tension upon the lifted pile forming 50 threads until after the lay has completed or substantially completed its beat-up movement, as will be later described.

Mounted upon the lower shaft 9 is the cam 23 having a dwell portion extending 55 between the points *a* and *b*, and riding upon the cam 23 is a roller 24 carried by a lever 25 which is pivoted at 26 to a bracket or stand 27 at the lower part of the loom frame, the construction being such that the lever 25 will be rocked upon its pivotal support

by the cam 23 and will be held with the roller 24 raised for a period of time to impart to the griff the desired movement.

Pivotedly connected to the lever 25 at 28 is the rod 29 preferably formed with a turn 70 buckle adjustment 30 and extending upwardly to the jacquard overhead mechanism, where it is pivoted at 31 to an arm 32 secured to the cross-shaft 33 mounted in suitable bearings 34 carried by the frame 75 of the jacquard. Secured to and extending from the shaft 33 is the arm 35 which is connected by the rod 36 to the griff 22, the construction being such that the movements imparted to the lever 25 by the cam 23 will 80 be transmitted to the griff, and since the cam 23 serves to raise the griff and by its dwell portion between the points *a* and *b* maintain it raised during the beat-up movement of the lay, the figuring pile warp 85 threads selected by the jacquard mechanism will be held raised during the dwell of the griff.

Mounted upon the lower shaft 9 is a second cam 37 having a dwell portion between 90 the points *c* and *d* of somewhat less extent than the dwell portion *a* and *b* of the cam 23, and riding upon the cam 37 is the roller 38 carried by the lever 39, which is here shown as mounted for pivotal movement 95 upon the axis 26. The other end portion of the lever 39 is connected at 40 to an upwardly extending rod 41 for controlling the comber board. In the present instance of the invention, the upper portion of the rod 100 41 is pivotally connected at 42 to the arm 43 secured to the transverse shaft 44 mounted in the overhead framing, as indicated in Fig. 1. The shaft 44 has secured thereto the arm 45 connected by hangers 46 105 to the comber board 47, the construction being such that the comber board will be raised under the dictates of the cam 37 and dwell for a time in its raised position to thereby form the lower plane of the figuring 110 pile warp sheds, as indicated in Fig. 2.

Inasmuch as the comber board positions the figuring pile warp threads to float within the body of the fabric upon the formation of the figuring pile warp shed, the shaft 44 115 connected to the comber board is preferably counterweighted. This may be effectively done by a weight 48 secured to the rod 49 connected at its upper end at 50 to an arm 51 secured to the transverse shaft 44, and in 120 order to maintain proper movement of the rod 49, the lower end portion thereof is conveniently passed through a guide 52 secured to the loom frame.

The jacquard cylinder 53, as indicated in 125 Fig. 1, is given its usual movements towards and from the usual needles by eccentric mechanism, which in the present instance of the invention, consists of the eccentric 54, of which there may be one at each side of the 130

loom. As shown, the eccentric 54 is mounted upon the shaft 55 which is given its rotary movements by means of a pinion 56 secured to the shaft 55 and meshing with a gear 57 secured to the transverse shaft 17. The eccentric 54 is embraced by the eccentric strap 58 from which rises the rod 59 connected at its upper end at 60 to an arm 61, best indicated in Fig. 4. The arm 61 is secured 10 to the shaft 62 from which projects the arm 63 connected by a link 64 with a slide 65 mounted for movement in guideways 66 and carrying the jacquard cylinder 53, the effect being that upon rotation of the eccentric or 15 eccentrics, the jacquard cylinder will be moved to and from its operative position as usual to selectively engage the hooks of the jacquard with the usual knives of the griff 22. The eccentric actuation of the jacquard 20 cylinder is important, as giving to the cylinder positive and determined movements in all of its positions.

As indicated in Fig. 2, the multiplicity of 25 figuring pile warp threads *e* pass through the reed 67 carried by the lay 14, and similarly, the ground warp threads *f* pass through the reed.

During that cycle of loom operation for 30 formation of the figuring pile loops, the jacquard pattern, as usual, selects the figuring pile warp threads that are to be raised to form the pile loops, whereupon, the controlling cam 23 actuates through the train of mechanism described for raising the griff

35 to form the figuring pile warp shed, as indicated in Fig. 2, while the comber board positions the figuring pile warp threads that are not to form pile loops to float in the body of the fabric, as indicated in Fig. 2. 40 The pile wire 68 is thereupon inserted by the pile wire inserting mechanism and the ground shed is formed by the harness mechanism for the insertion of the weft thread 69. Owing to the dwell portions of the cams

45 23 and 37, the griff 22 will not only be raised by the cam 23 but will be held raised, thereby tensioning the figuring pile warp threads in the upper plane of the pile shed and take up any slack. At this time, also, the comber

50 board 47 will place the figuring pile warp threads to float within the body of the fabric. With the parts being in the position stated, the lay beats up, thereby forcing the pile wire 68 and the weft threads 69 to the fell 55 of the cloth, as indicated in Fig. 3, while the pile forming shed remains open, with the result that the slack being taken up in the pile forming warp threads which are to form the pile loops, only one beat-up movement of the lay is necessary. The result of this is that increased production of fabric results, the parts are simplified, and fabric of uniform surface and pattern is produced.

What is claimed is:

56 1. A loom for weaving figured pile fabrics

having a multiplicity of figuring pile warp threads and ground warp threads, comprising, in combination, the lay, transverse pile wire mechanism, a jacquard having a griff for selectively controlling the pile warp 70 threads, harness mechanism for controlling the ground warp threads, a cam for raising the griff and having a dwell portion for maintaining the griff raised and the lifted figuring pile warp threads under tension, and means for operating the lay to beat up the transverse pile wire and a weft thread simultaneously to the fell of the cloth during the dwell of the griff and consequent tension on the raised figuring pile warp threads. 75

2. A loom for weaving Wilton and similar figured pile fabrics having a multiplicity of figuring pile warp threads and ground warp threads comprising, in combination, the lay, transverse pile wire mechanism, a jacquard having a griff for selectively raising certain of the figuring pile 80 warp threads, harness mechanism for shedding the ground warp threads, a cam having a dwell portion, connections between the cam and griff for raising the griff and maintaining it raised with the selected figuring pile warp threads under tension during the insertion of the pile wire and a weft thread, and means for actuating the lay to beat-up the wire and weft thread simultaneously to the fell of the cloth while the tension is maintained upon the raised pile warp threads. 85

3. A loom for weaving Wilton and similar pile fabrics having a multiplicity of figuring pile warp threads and ground warp threads, comprising, in combination, the lay and operating means therefor, a transverse pile wire mechanism, a jacquard having a griff for selectively raising certain of the figuring pile warp threads, harness mechanism for shedding the ground warp threads for insertion of the weft threads, means for laying one weft thread 100 below all of the pile warp threads and a second weft thread above all of the pile warp threads, means connected to the griff for raising it and maintaining it raised with the lifted figuring pile warp threads under tension during the front movement of the lay to carry the pile wire and lower weft thread simultaneously to the fell of the cloth while the raised figuring pile warp threads are 105 under tension. 110

4. A loom for weaving Wilton and similar pile fabrics having a multiplicity of figuring pile warp threads and ground warp threads, comprising in combination, the lay and operating means therefor, transverse pile wire mechanism, a jacquard having a griff for selectively raising certain of the figuring pile warp threads, harness mechanism for shedding the ground warp threads for insertion of the weft threads, 120 125

means for laying a weft thread in the shed, means connected to the griff for raising it and maintaining it raised with the lifted figuring pile warp threads under tension 5 during the front movement of the lay to carry the pile wire to the fell of the cloth while the raised figuring pile warp threads are under tension, means for actuating the lay to beat-up a pile wire and weft thread simultaneously to the fell of the cloth, and 10 means for floating the unlifted figuring pile warp threads in the body of the fabric.

5. A loom for weaving Wilton and similar pile fabrics having a multiplicity of figuring pile warp threads and ground warp threads, comprising, in combination, the lay and operating means therefor, a jacquard having a griff for selectively raising 15 certain of the figuring pile warp threads, harness mechanism for shedding the ground warp threads for insertion of the weft threads, means connected to the griff for raising it and maintaining it raised 20 with the lifted figuring pile warp threads under tension during the front movement of the lay to carry the pile-wire and a weft thread simultaneously to the fell of the cloth while the raised figuring pile warp 25 threads are under tension, and thereupon acting to lower the griff and controlled figuring pile warp threads to form the pile loop.

6. A loom for weaving pile fabrics having a multiplicity of figuring pile warp threads and ground warp threads, comprising, in combination, the lay and operating means therefor, transverse pile wire inserting mechanism, a jacquard having a griff for selectively raising certain of the multiplicity of figuring pile warp threads to form the upper plane of the pile shed, a 35 comber board for controlling the other figuring pile warp threads to form the lower 40 plane of the pile shed, harness mechanism for forming the ground shed, a cam for raising the griff and provided with a dwell portion for maintaining the griff raised and the 45 lifted figuring pile warp threads under tension in the upper plane of the pile shed during the beat-up movement of the lay to beat the pile wire to the fell of the cloth, a second cam having a dwell portion for 50 controlling the comber board and maintaining the other figuring pile warp threads in position to float in the body of the fabric, said cams thereupon acting to shift the figuring pile threads to form the pile loops.

7. A loom for weaving Wilton and similar 55 pile fabrics having a multiplicity of figuring pile warp threads and ground warp threads, comprising, in combination, the lay and its operating means, transverse pile wire inserting mechanism, a jacquard having a griff for selectively raising certain of the

multiplicity of figuring pile warp threads, harness mechanism for forming the ground shed, a cam having a dwell, a lever actuated by the cam and connected to the griff to raise it and maintain it raised and the lifted 70 figuring pile warp threads under tension during frontward movement of the lay to beat up the pile wire and a weft thread simultaneously to the fell of the cloth while the lifted figuring pile warp threads are 75 under tension, and means for maintaining the other figuring pile warp threads in position to float in the body of the fabric.

8. A loom for weaving Wilton and similar pile fabrics having a multiplicity of figuring pile warp threads and ground warp threads, comprising, in combination, the lay and its operating means, transverse pile wire inserting mechanism, a jacquard having a griff for selectively raising certain of the 80 multiplicity of figuring pile warp threads, harness mechanism for forming the ground shed, a cam having a dwell, a lever actuated by the cam and connected to the griff to raise it and maintain it raised and the lifted 85 figuring pile warp threads under tension during frontward movement of the lay to beat up the pile wire to the fell of the cloth while the lifted figuring pile warp threads are under tension, a second cam having a 90 dwell portion for maintaining the other figuring pile warp threads in position to float in the body of the fabric.

9. A loom for weaving Wilton and similar pile fabrics having a multiplicity of figuring pile warp threads and ground warp threads, comprising, in combination, the lay and its operating means, transverse pile wire inserting mechanism, a jacquard having a griff for selectively raising certain of the 100 multiplicity of figuring pile warp threads, harness mechanism for forming the ground shed, a cam having a dwell, a lever actuated by the cam and connected to the griff to raise it and maintain it raised and the lifted 105 figuring pile warp threads under tension during frontward movement of the lay to beat up the pile wire to the fell of the cloth while the lifted figuring pile warp threads are under tension, a second cam having a dwell portion of less extent than the dwell portion of the other cam to cause the other figuring pile warp threads to float in the body of the fabric.

10. A loom for weaving Wilton and similar pile fabrics having a multiplicity of figuring pile warp threads and ground warp threads, comprising, in combination, the lay, transverse pile wire inserting mechanism, a jacquard having a griff for selectively raising certain of the figuring pile warp threads to form the pile shed, harness mechanism for shedding the ground warp threads, a cam shaft, a cam having a dwell portion secured to said shaft, a lever 110 120 125 130

actuated by the dwell cam, a rod connection between the lever and griff for raising the griff and holding it raised with the selected figuring pile warp threads under tension 5 during the beat-up movement of the lay, a second cam on the cam shaft provided with a dwell portion, a second lever actuated by said second cam, and a rod connection be- tween the second lever and comber board that the dwell portions of the cams may main- 10 tain the figuring pile warp shed open during the beat-up movement of the lay.

In testimony whereof, I have signed my name to this specification.

HOWARD MASON.
